UNITED STATES PATENT OFFICE.

SAMUEL C. HUBBARD, OF MIDDLETON, CONNECTICUT, ASSIGNOR TO CHARLES C. HUBBARD.

MACHINE FOR GRADUATING LINEAL MEASURES.

Specification of Letters Patent No. 17,606, dated June 16, 1857.

To all whom it may concern:

Be it known that I, SAMUEL C. HUBBARD, of Middletown, in the county of Middlesex and State of Connecticut, have invented certain new and useful Improvements in Machines for Graduating Lineal Measures, of which the following is a full, clear, and exact description, reference being had to the accompanying drawings, which make part of the specification, and in which—

Figure 1 represents a side elevation of a machine having my improvements applied thereto; Fig. 2 represents a top view thereof; and Fig. 3 an elevation of one end of the same.

My improved machine is more especially designed for the graduation of folding pocket rules, and it consists of a strong frame or bed (A) with rails (a) on its top, for a carriage (B) to slide on, which carries graduated dies to imprint the divisions and numerals upon the rule. On each side of the bed frame (A) a standard (C) is erected, and these standards support the horizontal axis of a thick disk (D) whose office it is to press the rule upon the dies to indent the marks of the latter, upon the former in a manner to be presently described.

The carriage (B) has a reciprocating motion upon the rails or guides (a) which is communicated to it in this instance by straps (E) connected to a shaft (F) in the frame, in such manner that when the shaft (F) is turned in one direction the one strap will be unwound from the shaft and the other wound upon it; the strap at the end of the carriage which for the time is approaching the shaft being wound up, and that attached to the end of the carriage which is receding from the shaft being let out; with this arrangement it is obvious that a reciprocating motion is easily communicated to the carriage by attaching a winch (G) to the shaft, and turning it in alternately opposite directions.

A central rib (H) extends along the top of the carriage and on each side of this rib two studs (I) are placed, the dies which consist of oblong blocks of metal are placed between this central rib and the studs, and the set screws (J) which pass through the studs secure the dies firmly to the rib, and as there is a die on each side of the rib the two edges of the same rule, or one edge of each of two

adjacent rules may be graduated at once by 55 pressing the same down upon the dies. As rules of different widths have to be graduated the dies are set at different distances from the central rib (H) by means of set screws projecting therefrom and the set or clamp 60 screws (J) which pass through the studs (I).

The upper faces of the dies have all the characters formed upon them in relief, which it is desired to imprint on the rule to be graduated. The top of the dies extends so 65 near to the lowest part of the periphery of the disk that when a rule is laid upon them to be stamped, and the carriage moved beneath the disk, it can only pass under the latter by forcing the rule down upon the face 70 of the die with a high degree of pressure, which insures the imprinting of the graduation marks.

As the folding pocket rule has several joints, some of which project considerably 75 above the face of the rule, it becomes necessary to prevent the crushing of the joints to provide corresponding indentations in the face of the dies, and in the periphery of the disk; and in order that these indentations in 80 the disk may always meet the joints of the rule, it is necessary that the disk should begin its motion in a determinate position. To insure this the side of the disk is fitted with a pin (K) which strikes against a stop (L) 85 on the frame and is held there by the tension of a spring (M) coiled around the shaft (N) and as the disk is turned by friction alone it always commences turning when the rule on the dies bears against it in passing under, in 90 this way the position of the disk in starting with respect to the rule is always the same.

The rule represented in Fig. 4 shows the manner in which the dies graduate it, and the rule in Fig. 5 represents additional or 95 gage lines (c) parallel to the edges, and at right angles to the graduation marks of the rule. These gage lines are produced by sharp-pointed instruments (P) held by a bracket immediately behind the disk, so 100 that the progressive movement of the carriage will bring the rule under those points and scratch or cut the lines to the requisite depth.

The movements and construction of the 105 several parts can readily be modified to a considerable extent, without changing the character of the invention in the least, but as

such changes as these are quite obvious, I have not deemed it necessary to describe them.

- 5 1. I claim in combination with dies for imprinting the figures and transverse lines upon the rule, gravers or points, arranged and held as described, for marking the gage or longitudinal lines on the rule as described.
- 10 2. I also claim the pressure disk (D) with one or more indentations on its periphery corresponding to the knuckles of the joints of

folding rules, when this is combined with giving to the disk thus constructed a self-acting reverse motion to bring it back after each 15 impression of a rule, to the precise point whence it started, substantially in the manner and for the purpose herein specified.

In testimony whereof I have hereunto subscribed my name.

SAML. C. HUBBARD.
